(57) **CLAIM**

The ornamental design for a flashlight, as shown and described.

DESCRIPTION

FIG. 1 is a front, left side, top perspective view of a flashlight showing my new design;
 FIG. 2 is a rear, right side, bottom perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof;
 FIG. 8 is a bottom plan view thereof;
 FIG. 9 is an enlarged view of the encircled region 9 shown in FIG. 1;
 FIG. 10 is an enlarged view of the encircled region 10 shown in FIG. 2; and,
 FIG. 11 is a cross-sectional view of the flashlight as taken along the section line 11-11 as depicted in FIG. 5.
 The broken lines depict portions of the flashlight that form no part of the claimed design.
